Primary Examiner — Messina L Smith*Assistant Examiner* — Elizabeth Borsetti(74) Attorney, Agent, or Firm — CANTOR COLBURN LLP(57) CLAIM

The ornamental design for a cosmetic bottle, as shown and described.

DESCRIPTION

FIG. 1 is a perspective view of a cosmetic bottle showing my new design;

FIG. 2 is a front view thereof;

FIG. 3 is a rear view thereof;

FIG. 4 is a side view thereof;

FIG. 5 is another side view thereof;

FIG. 6 is a top plan view thereof; and,

FIG. 7 is a bottom plan view thereof.

The broken lines illustrating portions of the cosmetic bottle form no part of the claimed design.

1 Claim, 6 Drawing Sheets(56)
